CLAIM

The ornamental design for a ceiling light, as shown and described.

DESCRIPTION

FIG. 1 is a perspective view of the bottom of a ceiling lamp which embodies the design and which comprises a pair of curved reflectors, a spill shield between and below the reflectors, and a pair of diffusers which extend between the spill shield and the respective reflectors on opposite sides of a fluorescent tube (not shown). The fluorescent tube does not constitute part of the design;

FIG. 2 is an enlarged fragmentary view showing one end of the reflectors and the spill shield of the ceiling lamp of FIG. 1; and,

FIG. 3 is an enlarged fragmentary view similar to FIG. 2 but showing one of the diffusers of the ceiling lamp of FIG. 1.
